HENRY MARTIN, OF CHICAGO, ILLINOIS, ASSIGNOR TO HIMSELF, A. H. TOWNE, AND A. J. AMBLER.

Letters Patent No. 61,222, dated January 15, 1867.

IMPROVED METALLIC SAFETY SEAL FOR RAILROAD CARS.

The Schedule referred to in these Letters Patent and making part of the same.

TO ALL WHOM IT MAY CONCERN:

Be it known that I, HENRY MARTIN, of Chicago, Cook county, State of Illinois, have invented a Metallic Seal for Railroad Cars; and I do hereby declare that the following is a full, clear, and exact description thereof, reference being had to the accompanying drawings, making a part of this specification, in which—

Figure 1 is a perspective view of the seal ready for use.

Figure 2 shows the same when its ends are fastened together.

Figure 3 is a sectional view of the eyelet fastening.

Similar letters of reference indicate corresponding parts in the several figures.

This invention is designed for the better security of railroad cars from loss by theft, by furnishing information at what point on a road a car may have been opened. It consists in a simple device, which is so constructed that it can be readily attached to the locks, bolts, or other fastening of a car door, in such manner that the door cannot be opened without breaking or so mutilating the device that the fact will at a glance be discovered, as will be hereinafter described.

To enable others skilled in the art to understand my invention, I will describe its construction and operation.

The metallic seal, which I have represented in the drawings, is made of a thin strip of metal of any required length, and gradually tapering from its extremities to its centre, *b*, so that this latter point of the sealing strip will be much narrower than its ends. These strips may be cut out of scrap tin, or other thin metal, by suitable machinery, so that they can be sold very cheap; and in forming them a hole, *a*, is made near each end, of a suitable size to receive a common eyelet. These strips are bent in the centre or smallest part, as shown in fig. 1, and they are ready for use. The mode of using them is to insert one end through a staple, lock, eye, or other projection from a car door which forms part of its fastening, then press the ends of the strip together, insert an eyelet, *c*, through the holes *a a*, and, with nippers that are adapted to the purpose, clinch the eyelet firmly. With the common eyelet-clinching nippers the ends of the eyelets can be so firmly spread out and pressed into the metal of the seal that it would be impossible for a person to separate the ends of the seal again without such fact appearing. Should the fastenings on the doors of cars not admit of the use of this seal, staples may be driven into the doors and their jambs above or below the fastenings for receiving the seals. The object of making the strips narrower in the middle than at their ends is to admit of their being readily broken when it is desired to open a car door; also to afford the required amount of metal at the ends of the strips for receiving the eyelet fastenings.

Having thus described my invention, I claim as a new and useful article of manufacture—

A metallic seal, consisting of a tapering strip of metal which is constructed for receiving an eyelet, and having its ends secured together thereby, substantially as described.

HENRY MARTIN.
